UNITED STATES PATENT OFFICE.

JOHN CUNNINGHAM, OF UKIAH, CALIFORNIA.

TRUSS.

1,345,139.

Specification of Letters Patent. Patented June 29, 1920.

Application filed December 14, 1918. Serial No. 266,736.

To all whom it may concern:

Be it known that I, JOHN CUNNINGHAM, a citizen of the United States, residing at Ukiah, in the county of Mendocino and State 5 of California, have invented certain new and useful Improvements in Trusses, of which the following is a specification.

This invention relates to trusses, and pertains especially to the class of trusses employing a spiral spring for controlling the 10 pressure of body contact pads.

The object of the invention is to provide a truss the several parts of which are adjustable with respect to each other, and certain 15 of said parts are self adjusting according to the movements of the body of the wearer.

A further object of the invention is to provide in a truss, such connection between the 20 pad spring, the leg strap and the waist band as to permit free circular movement of the strap end and the band ends on the spring according to the movement of the body of the wearer without changing or varying the 25 pressure of the spring on the pad.

A still further object of the invention is to provide a pad of novel and peculiar shape or construction, and a spiral spring having one end loosely fitting within the pad, and 30 the other end of the same diameter for holding the ends of a waist band and the end of a hip strap in circular movement during the fixed position of the pad in proper position on a wearer.

Various other objects, advantages and improved results are attainable in the practical application of the invention as herein-after disclosed.

In the accompanying drawings forming 40 part of this application:

Figure 1 is a perspective view.

Fig. 2 is a vertical sectional view of the pad and the spring with the strap removed and showing the band ends hooked to the 45 spring.

Fig. 3 is an inverted elevation of part of the spring showing the strap and band hooks applied, the movement of the hooks being shown in dotted lines.

Fig. 4 is an elevation of the body-bearing face of the pad.

Fig. 5 is a detail section of part of a pad and spring the dotted lines showing the movement of the pad lip.

Fig. 6 is a front view of part of a truss 55 for double rupture.

In carrying out my invention I employ preferably fabric webbing for the waist band 1, and for the strap 2, the latter is narrower and may be of lighter weave than 60 the band which is desirably wide and of sufficient textural weave or weight as to remain in flat position when worn. Each end of the band is provided with a buckle comprising a pivoted bail 3 having piercing points 4, and a rigid frame 5 having a hook 6 projecting forward or toward the ends of the band 1. One end of the strap 2 has a loop 7 slidable on the band, and the other end of the strap is provided with a buckle 65 8 having a hook 9 projecting therefrom. The hooks 6 and 9 engage the outer end of a spiral spring 10 for free circular sliding movement with respect to the spring in applying the truss and according to the movements of the body of a wearer. The other or inner end of the spring is of the same 70 diameter as the outer end, so that the spring is of the same diameter throughout, and is 75 not cone shaped as such springs are usually made. My spring affords means for free circular movement of the hooks so that they may adjust themselves for direct pressure on the spring perpendicular to the pad 11, under the pull or tension of the band and 80 strap in wearing position. Contrary to the usual cone spiral springs there is no central compression of one end of my spring, but the 85 compression and expansion of my spring is uniform throughout so that the outer end is always opposite the inner end, and there is no possibility of disalignment of the spring under various movements of the wearer. The self-adjusting hooks 6 and 9 90 equalize the pull of the band and strap on the spring so as to prevent tilting of the spring in the pad seat and keeps the spring in perfect alignment under all conditions and 95 positions of the wearer, without the usual and uncertain adjustments of the strap, band 100 and spring.

The pad 11 is preferably composed of a circular body of rubber and comprises an outer face forming a seat 12 for the spring, a beveled annular flexible lip 13 overhanging said seat and adapted to permit the inner end of the spring to be pressed thereunder into the seat and to be expeditiously 105

removed. The inner or body contact face of the pad comprises an annular surface 14 forming a bearing for the wall of a rupture opening, and a central circular protrusion 15, slightly convexed for fitting such opening and forming a bearing for a rupture.

It will be seen that the spring seat is opposite the wall bearing 14, that the rupture bearing 15 is not affected by spring pressure, and that the slight central protrusion of the pad is sufficient to fit a rupture opening and keep the rupture in natural position without pushing and undue pressure. This from practical experience with a multitude of pads and trusses on my own rupture is highly essential and of great practical importance for comfort and utility. The same is true of my method of connecting the strap 20 and band ends with the spring so as to permit free circular movement of said ends in self-adjustment for controlling the tension of the spring on the pad. Obviously after the buckles are once adjusted on the strap 25 and the band for a wearer, there is no further adjustment thereof required, and such other adjustment is afforded by merely applying the hooks to the spring.

In view of the simplicity of my truss it 30 will be seen that one or the other of the band hooks may not be removed from the spring in applying the truss, that the spring and pad is free to be adjusted to the most comfortable position after the strap and 35 band has been hooked to the spring, and that the strap being hooked between the band

hooks equal pressure is applied around the spring.

I do not wish to confine myself to any particular size and material in the construction 40 of any of the parts of my truss, but reserve the right to make such changes and variation in the manufacture and practical application thereof as may come within the scope 45 of the appended claim.

Obviously this truss may be used for either right or left rupture, and in the case of a double rupture, the parts hereinbefore described are duplicated and the springs are connected by a short strap 16 having a 50 buckle 17 and hooks 17^a, as clearly shown in Fig. 6 of the drawings.

Having thus described my invention what I claim as new and desire to secure by Letters Patent is:

In a truss of the character described, a waist band, a hooked buckle on each end of the band, a pad, a coiled pad spring intervening the buckles and to which the hooks are slidably attached so as to permit free 60 circular movement of the hooks on the spring with respect to each other, and a perineal strap slideable on the band and having a buckle hook for free circular movement on the spring between the band buckle hooks, 65 substantially as set forth.

In testimony whereof I affix my signature in presence of two witnesses.

JOHN CUNNINGHAM.
